UNITED STATES PATENT OFFICE

121,511

DESIGN FOR A COMBINED LAMP AND LIQUID DISPENSER

Harry H. Johnson, Brookline, Mass., assignor of
one-half to Charles Poulos, Boston, Mass.

Application April 25, 1940, Serial No. 91,951

Term of patent 14 years

To all whom it may concern:

Be it known that I, Harry H. Johnson, a citizen of the United States, residing at Brookline, in the county of Norfolk and Commonwealth of Massachusetts, have invented a new, original, and ornamental Design for a Combined Lamp and Liquid Dispenser, of which the following is a specification, reference being had to the accompanying drawing, forming a part thereof.

Figure 1 is a front elevation of a combined lamp and liquid dispenser, embodying my new design.

Figure 2 is a side elevation of the same.

I claim:

The ornamental design for a combined lamp and liquid dispenser, as shown.

HARRY H. JOHNSON.
